UNITED STATES PATENT OFFICE

158,262

FRIED CHICKEN SUPPORTING RACK OR SIMILAR ARTICLE

John E. Goding, Ontario, Calif.

Application January 13, 1949, Serial No. 218

Term of patent 14 years

(Cl. D44—29)

To all whom it may concern:

Be it known that I, John E. Goding, a citizen of the United States of America, residing at Ontario, in the county of San Bernardino and State of California, have invented a new, original, and ornamental Design for a Fried Chicken Supporting Rack or Similar Article, of which the following is a specification, reference being had to the accompanying drawing, forming part thereof.

Fig. 1 is a perspective view of a fried chicken supporting rack, showing my new design; and

Fig. 2 is a top plan view thereof.

I claim:

The ornamental design for a fried chicken supporting rack or similar article, as shown.

JOHN E. GODING.
